H. S. LION

BOX

Filed June 9, 1926

INVENTOR.

Harold S. Lion
BY
Allard Allen
ATTORNEY.

UNITED STATES PATENT OFFICE.

HAROLD S. LION, OF CINCINNATI, OHIO, ASSIGNOR, BY MESNE ASSIGNMENTS, TO UNITED MILK CRATE COMPANY, OF CINCINNATI, OHIO, A CORPORATION OF OHIO.

BOX.

Application filed June 9, 1926. Serial No. 114,821.

My invention relates to boxes and crates for the shipping of goods, which boxes are intended to be returned to the shipper when empty, and it has particularly to do with 5 such crates designed for the transportation of milk and other bottles.

Such boxes are necessarily subjected to exceedingly hard usage, and it is essential that they shall be strong and durable, and 10 also capable of repairs when damaged.

The invention belongs to that class of such crates as are formed of strips or slats of wood for the sides and ends, open at the top, and divided into compartments by metallic 15 cross wires, and usually with a bottom of wire rods, although for certain articles, as groceries, a closed bottom is used.

It is the object of my invention to provide such a crate with mortised and tenoned sides 20 and ends, and securely bound at the corners both inside and out, with angle plates or corner irons, and the invention has especially to do with that certain novel construction for interlocking the corner irons and for fitting 25 the wooden slats thereto, so that in case of breakage, any damaged slat may be readily replaced.

As the invention has especially to do with the corner construction, I have not thought 30 it necessary to illustrate the entire crate, the construction for one corner being the same for the other three corners.

In the drawings:—

Figure 1 is a perspective view of an out- 35 side corner iron.

Figure 2 is a similar view of the cor- 40 responding inner corner.

Figure 3 is a perspective view illustrating the fit of the slats at the corners.

Figure 4 is a perspective view of a detail 45 of a corner with both corner plates in place.

Figure 5 is a section of the corner as shown in Figure 4, taken through the corner plates, as indicated by the lines 5—5.

Figure 6 is a perspective of one of the bottom caps.

Figure 7 is a cross section of the outside corner plate, taken on line 7—7 of Figure 1.

The body of the crate is constructed of 50 strips or slats of wood 1 and 2 of the desired length and dimensions for the sides and ends of the box. The ends of each of these strips are oppositely notched or mortised so as to leave tenons 3, 3, and 4, 4, so that the

corners will fit together, and each strip is 55 provided with a saw kerf or groove 6, 7 on the outer face, so that the grooves will register when the sides and ends are fitted together.

The corner plates 12 for the outside are 60 bent to form a right angled structure, and ears 8, 8, are cut and bent over inwardly at right angles to the respective plate walls. These ears project at the proper distances 65 apart, to receive the respective tiers of slats, and each corner plate 12 is provided with a re-entering flange 10, 10, to engage within the respective grooves 6 and 7 of the slats.

In assembling the construction, the re- 70 spective slats 1 and 2 are fitted together to form tiers, and the outside corner plates 12 are then fitted in place, with the ears inserted between the respective tiers. The corner plates, which are constructed pref- 75 erably of galvanized sheet metal, can be sprung so that the flanges 10, 10, will engage in the grooves.

Inside locking plates are provided, bent 80 centrally at right angles with slots 14 cut to receive the projecting ends of the ears 8, 8 and the ends of the ears are then clinched over as shown at 15, thus securely locking 85 the inside and outside plates together and providing an exceedingly strong and rigid structure for the corners of the box.

Caps are provided for the bottom cor- 90 ners as shown in Figure 6, to fit the bottom corners with outside walls 16, a base 17, and upwardly projecting portions 18. These caps are seated in the recessed ends of the 95 corners so as to come flush with the bottom edges of the box, as is usual, so that the boxes can slide on the surface upon which they rest, and similar caps are provided for the upper corners, except that the upper caps have upward projections at the outside 100 edges to permit the boxes to be stacked one above the other. This construction is common for such boxes, and I have therefore not illustrated it. The caps are then riveted in 105 place, and the necessary bottom and compartment partitions secured in place, and the box is complete.

In the event that any of the slats are damaged or broken, it is comparatively simple 105 and easy to replace a broken slat. The caps are removed, and the inner locking plates re- moved upon releasing the ears, the outside

corner plates can then be removed and the broken part renewed and the box reassembled at much less time and expense than the replacement with a new box.

Having thus described my invention what I claim as new and useful and desire to secure by Letters Patent is:—

1. A box having side and end walls composed of a frame of wooden strips arranged in tiers, with a metallic angle plate for the outside of each corner of the box having ears punched therefrom extending inwardly, horizontally, flatwise, and at right angles to the plate, and a locking plate for the inside of each corner provided with slots to receive

said ears of the outside plate for clinching, to secure the corner plates in position.

2. A box having side and end walls composed of a frame of wooden strips arranged in tiers, with the ends of the strips mortised and tenoned to interlock, with a metallic angle plate for the outside of each corner of the box having ears punched therefrom extending inwardly, horizontally, flatwise, and at right angles to the plate, and a locking plate for the inside of each corner provided with slots to receive said ears of the outside plate for clinching, to secure the corner plates in position.

HAROLD S. LION.
